CARD HOLDER

Carroll E. Roche, Cincinnati, Ohio

Application June 10, 1936, Serial No. 84,575

2 Claims. (Cl. 40—16)

This invention relates to a card holder for holding identification cards, price cards, and the like, and has for its principal object the improvement of a device of the character stated to the end that the card is securely held for display.

The further object of the invention is the provision of a means whereby identification cards, such as those used by laundries for barbers' coats and the like that have heretofore been identified by the name of the wearer embroidered into the coat, the means provided consisting of a detachable card holder, so that should the original wearer of the coat discontinue wearing it, the coat or other article may be used for another wearer and thus prevent loss to the laundry or the expense of removing the embroidered name and substituting another embroidered name therefor.

The invention will be described in detail hereinafter and will be found illustrated in the accompanying drawing in which:

Figure 1 is a front view in elevation of the improved card holder;

Figure 2 is an end view;

Figure 3 is a rear view;

Figure 4 is a transverse section on a plane indicated by the line 4—4 of Figure 1, and

Figure 5 is a longitudinal sectional view on a plane indicated by the line 5—5 of Figure 1.

In the drawing similar reference characters are used to designate corresponding parts in all of the views.

As disclosed in the drawing the card holder comprises a plate 10 of any suitable material, such for instance as sheet metal, celluloid, and the like, and has its edges returned on three sides as shown at 11 to provide a recess 12 to engage and hold the corresponding edges of an identification card 13, said card to be used for the name and address of the wearer of the laundered article, or obviously the card may be used for a price card or any special advertising matter that might be imprinted thereon for display.

On the rear side of the plate 10 are provided spring clips 14 consisting of elongated tongues

as shown that are secured at one of their ends 15 to the plate 10 in any suitable manner, said tongues being formed of any suitable resilient material, and have their free terminals provided with enlarged buttons that may be circular as shown in the drawing or any other shape that may be preferred, said buttons being designated 16, and providing an enlarged clamping surface for the tongues and having marginal flanges 16a for engagement by a thumb or finger nail, providing means for manually releasing the tongues from clamping engagement when removing the plate and card frame from an article.

In use it will be apparent that the large plate and frame may be attached to the inner pocket 15 of a coat or secured to any article as may be desired by means of the clips 14 and the structure, as hereinbefore stated, lends itself to providing means whereby the identification card or card for any other use may be readily removed and 20 replaced.

I claim as my invention:—

1. A card holder, comprising a frame member adapted to receive and retain an identification card or the like, spring clips secured to said 25 frame adjacent opposite sides and within the area of the frame and adapted to secure it in position for display of said card, a button on the free end of each clip, and a marginal flange on each button for engagement by a thumb or finger nail in releasing the clip.

2. A card holder, comprising a plate, edges of said plate returned on its intermediate portion and providing recesses for receiving the edges of an identification card, spring clips secured to said 35 plate adjacent opposite sides and within the area of the plate, each of said clips being a tongue of resilient material, secured at one terminal to the plate, and a button on the free end of the tongue providing an enlarged clamping surface, and a 40 marginal flange on said button for engagement by a thumb or finger nail in releasing the clip.

CARROLL E. ROCHE.
